UNITED STATES PATENT OFFICE.

GEORGE L. CAMPBELL, OF WILLIAMSPORT, PENNSYLVANIA, ASSIGNOR TO
CHET S. HILL AND J. B. H. TRAINER, BOTH OF SAME PLACE.

BORING-MACHINE.

SPECIFICATION forming part of Letters Patent No. 447,176, dated February 24, 1891.

Application filed May 3, 1890. Serial No. 350,490. (No model.)

To all whom it may concern:

Be it known that I, GEORGE L. CAMPBELL, of Williamsport, in the county of Lycoming and State of Pennsylvania, have invented a 5 new and Improved Boring-Machine, of which the following is a full, clear, and exact description.

The object of the invention is to provide a new and improved boring-machine which is 10 simple and durable in construction, very effective in operation, and specially designed for conveniently boring holes in joists of a ceiling or floor for the passage of concealed electric wires.

15 The invention consists in certain parts and details and combinations of the same, as will be described hereinafter, and then pointed out in the claims.

Reference is to be had to the accompanying 20 drawings, forming a part of this specification, in which similar letters of reference indicate corresponding parts in all the figures.

Figure 1 is a front elevation of the improvement. Fig. 2 is a side elevation of the same, 25 with parts in section. Fig. 3 is a plan view of the same, with parts in section; and Fig. 4 is an enlarged transverse section of the drill-shaft.

The improved boring-machine is mounted 30 on a suitably-constructed frame A, provided on its lower end with a rod B, having a crook B', adapted to be set on the operator's knee to support the frame A while boring.

In the lower part of the frame A is mounted 35 to turn the main driving-shaft C, on one end of which is secured a crank-arm D for conveniently turning the said shaft C. On the latter is secured a sprocket-wheel E, over which passes an endless sprocket-chain F, 40 also passing over a sprocket-wheel G, mounted to turn on a stud H, held in one side of the rectangular auxiliary frame A', secured on the upper end of the main frame A at right angles thereto.

45 On one face of the sprocket-wheel G is formed a bevel gear-wheel I, which meshes into a bevel gear-wheel J, keyed upon a sleeve K, mounted to turn in one side of the auxiliary frame A', as is plainly shown in Fig. 3.

50 Through this sleeve K passes the drill-shaft

L, carrying at its front end the drill or boring-tool N and provided at its other end with a screw-thread L', screwing in a nut A², formed in the auxiliary frame A'. On the drill-shaft L is also formed a key or feather L², fitting 55 into a correspondingly-shaped groove or slot K', formed in the sleeve K. (See Figs. 3 and 4.) When the main shaft C is rotated, a rotary motion is imparted to the sprocket-wheels E G, the sprocket-chain F, and the bevel gear-wheels I and J to the sleeve K, which in turn rotates the drill-shaft L. The rotary motion of the latter causes its threaded end L' to screw 60 in the nut A², so that the drill-shaft is fed forward or backward, according to the direction in which the main shaft C is turned.

On the main frame A is arranged an auxiliary frame P, which supports a bracket O, provided near its upper end with a vertically-extending plate Q, held in front of the boring-tool N and extending at right angles to the same. An aperture Q' is formed in the said plate Q, and through it can pass the boring-tool when the shaft L is fed forward, as previously described, in order to drill or bore 75 a hole in the joist on which the machine is to be applied.

On the bracket O is fulcrumed at R' an L-shaped lever R, guided at one end in an aperture Q², formed in the plate Q, the outer 80 end of this arm of the lever R being provided with an upward extension R², arranged parallel with the plate Q. The lower end of the lever R is provided with a handle R³ and is adapted to engage notches in a segmental arm 85 S, secured on the bracket O. The extension R² is provided with inwardly-projecting lugs or points R⁴, adapted to engage the back of the beam or joist T, on the front of which abuts the plate Q, as plainly illustrated in 90 Fig. 2.

When the operator desires to bore an aperture through the joist or beam T for the passage of the electric wires or for other purposes, he first moves the main frame A into 95 such a position that the plate Q abuts against one side of the joist, and then the handle end R³ of the lever R is swung outward toward the joist, so as to move the upper end of the said lever with the extension R² inward against the 100

other side of the joist T, the lugs R⁴ embedding themselves in the joist. The underside of the joist T is engaged by the horizontally-extending part of the lever R, so that the 5 drill-shaft L now stands at right angles to the joist T, and when the operator turns the crank-arm D to rotate the shaft C the drill-shaft L is also rotated and fed forward, as previously described, so that the boring-tool N passes 10 through the opening Q' in the plate Q and bores a hole in the joist T. When the hole has been bored, the operator reverses the movement of the crank-arm D, so as to turn the drilling-tool N out of the joist T. The next 15 joist is operated on in the same manner, and it will be seen that all apertures bored into the joists by the machine can be brought into the proper alignment, as the said apertures will be at right angles to the sides of the beam. 20 The auxiliary frame P is provided with side arms P', passing over the sides of the frame A, and each arm is provided with a lug P², adapted to engage one of a series of apertures formed in the sides of the frame A, as shown 25 in Figs. 1 and 2, so as to lock the frame P in place on the main frame A. When the operator desires to bore a hole above the one already bored, he moves the arms P' outward and presses on the fork B', so as to slide the 30 main frame A upward until the tool N is the proper distance above the hole already bored, the auxiliary frame remaining stationary. When the frame A has been adjusted to the proper place, the operator lets go of the arms 35 P', so that the lugs P² snap into the registering apertures in the sides of the frame A.

The operation above described in reference to setting the tool N in motion is repeated and an aperture is bored above the first one.

40 Having thus described my invention, what I claim as new, and desire to secure by Letters Patent, is—

45 1. A hand implement of the character described, comprising the open two-part rectangular frame A A', the boring-bit mounted in the part A' at right angles to the part A, an operating mechanism, and the auxiliary sliding frame P, sliding vertically on the side bars of the part A and having an outwardly-pro-

jecting bracket R, provided with clamping- 50 plates in front of and at right angles to the said boring-bit, substantially as described.

2. A hand implement of the character described, comprising the open two-part rectangular frame A A', the part A being provided 55 in its side bars with apertures, the boring-bit mounted in the part A' at right angles to the part A and provided with an operating mechanism, the vertically-sliding auxiliary frame P, having side arms P', provided at their lower ends with lugs P², engaging said apertures, and a bracket projecting from said auxiliary frame and having a plate at its outer end at right angles to the boring-bit, substantially as described. 60

3. A hand implement of the character described, comprising the two-part open frame A A', the bit mounted in the part A' and provided with operating mechanism, the auxiliary frame P on the part A, provided with an 70 outwardly and upwardly projecting bracket having a plate Q at its outer end at right angles to the bit, a lever R, pivoted between its ends to the bracket, passed through a slot Q² therein, and having a plate R² at its outer upper end and a handle portion at its lower end, and means for locking the said lever, substantially as described. 75

4. An implement of the character described, consisting in the two-part open frame A A', 80 the rod B at the lower end of part A and having a crook B', the main drive-shaft C, having a wheel, the wheel G in the upper part A' of the frame, provided with a gear I and driven from the wheel on shaft C, the nut A² in one 85 side of the part A', the sleeve K, crossing the part A' in the line with the nut and provided with a gear J, meshing with gear I, the threaded-bit shank L, passing through said sleeve and nut, a spline and groove connecting between said sleeve and shank, the sliding auxiliary frame P, having the bracket O, provided with plate Q, and clamping-lever R, having a plate R², substantially as described. 90
